(57) **CLAIM**

The ornamental design for a tablet pillow stand, as shown and described.

DESCRIPTION

FIG. 1 is a front, left, and top perspective view of a tablet pillow stand, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another perspective view of the tablet pillow stand, but showing the tablet pillow stand in use with a cell phone shown in broken lines.

The broken lines shown in the drawings represent environment that form no part of the claimed design.
